UNITED STATES PATENT OFFICE.

JOSEPH F. FRIEND AND PETER R. FRIEND, OF KENOSHA, WISCONSIN.

VAPORIZER.

1,378,780.

Specification of Letters Patent.

Patented May 17, 1921.

Application filed April 28, 1919. Serial No. 293,083.

To all whom it may concern:

Be it known that we, JOSEPH F. FRIEND and PETER R. FRIEND, citizens of the United States, residing at Kenosha, in the county of 5 Kenosha and State of Wisconsin, have invented new and useful Improvements in Vaporizers, of which the following is a specification.

This invention relates to vaporizers for 10 internal combustion engines, the object in view being to provide a device applicable to any engine whether used in connection with an automobile, motor truck, motor boat, flying machine or a stationary engine.

15 The broad object of the invention is to provide a device which will form what is known as a hot spot between the carbureter and the combustion chamber of the engine thereby enabling the inflowing fuel to be 20 broken up and vaporized and otherwise brought into a highly combustible condition before it is inducted into the combustion chamber of the engine.

25 With the above and other objects in view, the invention consists in the novel construction, combination and arrangement herein fully described, illustrated and claimed.

In the accompanying drawing:—

30 Figure 1 is a vertical sectional view illustrating the vaporizer in its applied relation to the intake pipe or manifold of an internal combustion engine.

Fig. 2 is also a vertical section through the same looking at a right angle to Fig. 1.

35 Fig. 3 is a plan view of the vaporizing attachment, showing the relation of the exhaust pipe of the engine thereto.

Referring to the drawings 1 designates the carbureter of an internal combustion engine, said carbureter being conventionally shown and being arranged at the receiving 40 end of the intake pipe or manifold 2 of said engine.

In carrying out the present invention I 45 provide a casing 3 which is preferably clamped between the flange 4 of the carbureter and the adjacent flange 5 of the intake pipe or manifold 2, said parts being secured together by means of bolts or other fastening members 6.

Extending centrally through the casing 3 and at a right angle to the longitudinal axis of the intake pipe or manifold 3 and also at a right angle to the normal direction 50 of flow of the incoming mixture, is a

pipe or connection 7 to one end of which is ordinarily attached an exhaust pipe 8 or a branch of the exhaust pipe of the engine for the purpose of conducting the hot exhaust gases through the intake manifold for the 60 purpose of heating the incoming mixture and producing a more highly combustible mixture for the engine.

The pipe or tube 7 contains a resistance coil 9 connected by suitable wire 10 with a 65 source of electrical energy such as a battery 11 which is shown as grounded at 12. A switch 13 is arranged in the circuit so as to control the flow of electrical energy to the resistance coil 9. In the use of the device, 70 preparatory to starting the engine in cold weather, the switch 13 is closed thereby causing the resistance coil 9 to become heated. In a short space of time, the wall of the connection or tube 7 becomes highly heated 75 and therefore when the engine is started, the vapor passing from the carbureter to the engine is highly heated and conducted to the engine in proper condition for ignition. As soon as the engine has run a sufficient 80 length of time to become heated, the switch 13 is opened and current is cut out from the resistance coil 9, the pipe or connection 7 being thereafter heated by the exhaust gases from the engine conducted thereto by 85 means of the exhaust pipe 8.

The device hereinabove described will be found very useful to motorists particularly in starting their cars in cold weather and is made in the form of an attachment so that 90 it may be readily combined with the necessary part of machines already in use, the device being fastened in place between the carbureter and the receiving end of the intake pipe or manifold, as clearly shown 95 in the drawing.

What we claim is:—

The combination with a carbureter having an attaching flange and an intake manifold having a flange, of a casing arranged 100 snugly between said first and second named flanges and securely attached to the same, said casing having its upper and lower sides formed with passages in alignment with said carbureter and said intake manifold, an 105 exhaust conveying pipe extending transversely through said casing between the upper and lower sides of the same and intersecting the longitudinal axis of said intake manifold, said exhaust conveying 110

pipe being provided with an attaching flange secured to said casing, and a heating coil arranged in tubular formation within said exhaust conveying pipe in spaced relation to the side walls of the same and extending longitudinally of the exhaust pipe to permit of the free flow of the exhaust

through the pipe, said heating coil intersecting the longitudinal axis of said intake manifold.

10

In testimony whereof we affix our signatures.

JOSEPH F. FRIEND.
PETER R. FRIEND.
